UNITED STATES PATENT OFFICE.

HORACE M. HOUSTON, OF WOODVILLE, TENNESSEE.

COMBINATION WALKING-CANE AND PICNIC-CHAIR.

SPECIFICATION forming part of Letters Patent No. 268,897, dated December 12, 1882.

Application filed October 3, 1882. (No model.)

To all whom it may concern:

Be it known that I, HORACE M. HOUSTON, a citizen of the United States, residing at Woodville, in the county of Haywood and State of Tennessee, have invented a new and useful Combination Walking-Cane and Picnic-Chair, of which the following is a specification, reference being had to the accompanying drawings.

Figure 1 is a side view, showing the device closed so as to form a cane. Fig. 2 is a perspective view, showing the device extended so as to form a chair or camp-stool; and Fig. 3 is a vertical sectional view.

Corresponding parts in the several figures are denoted by like letters of reference.

This invention relates to an improved combined walking-cane and camp or picnic chair, the construction of which will be hereinafter fully described, and particularly pointed out in the claims.

In the drawings hereto annexed, A represents a sleeve or body, made preferably of metal, and having notches B and C at its upper and lower ends respectively.

25 D D are the legs—three in number—which are hinged in the notches C, so as to be capable of being folded together, as shown in Fig. 1, so as to form the lower end of the cane. Similarly hinged in the notches B are braces 30 E, of which there may be six, and which are provided at their upper ends with notches F, in which the seat-bars G are hinged. The upper ends of said seat-bars are hinged to a suitable cap-piece, H.

35 I is a rod firmly secured to the cap-piece H, from which it extends downwardly between the bars G and braces E and through the sleeve or body A. Said rod I has a collar, J, which rests upon the said sleeve A when the 40 chair is extended. K K are braces hinged to the inner sides of the legs, and connected by a ring, L, through which the lower end of rod I extends. Said rod has a collar or stop, M, at its lower end, and another one, N, some distance above.

45 The legs, braces, and seat-bars, which are usually made of wood, all have a lining, O, of

brass or other suitable metal, which extends at the ends, so as to form the hinge parts, thereby imparting great strength and durability to the device. The upper and lower ends are screw-threaded to receive the head 50 P and ferrule Q, by which the parts are secured in position when folded.

The operation of my invention will be readily understood. To extend the chair, remove the head and ferrule, and, holding the body A with one hand, depress the cap H with the other. This will extend the seat. The collar N of rod I will serve to spread the braces K, thus 55 extending the legs. When the device is folded the collar M of rod I raises the braces K, thus 60 folding the legs.

I claim and desire to secure by Letters Patent of the United States—

65 1. The combination of a sleeve or body, legs hinged to the lower end of the same, braces hinged to its upper end, and seat-bars hinged between said braces, and a cap-piece having the downwardly-extending supporting-rod I, 70 as set forth.

2. The combination, with the sleeve or body, of the hinged legs, braces, and seat-bars, all having a lining of metal, which extends at the ends, so as to form the hinge parts, as set forth. 75

3. The combination of the sleeve A, having notches B C, legs D, having braces E, and seat-bars G, and cap-piece H, having rod I, provided with the collars J M N, as and for the 80 purpose set forth.

4. The combination, with the sleeve A, having hinged legs D and braces E, and the seat-bars G, cap-piece H, braces K L, and rod I, having collars J M N, of the screw-threaded head P 85 and ferrule Q, as and for the purpose set forth.

In testimony that I claim the foregoing as my own I have hereto affixed my signature in presence of two witnesses.

HORACE M. HOUSTON.

Witnesses:

J. M. JENKINS,
